UNITED STATES PATENT OFFICE.

SAMUEL GEORGE WILLIAM PHIPPS, OF LONDON, ENGLAND, ASSIGNOR TO RONEO
LIMITED, OF LONDON, ENGLAND, A COMPANY OF GREAT BRITAIN.

ADDRESSING OR LIKE PRINTING MACHINE.

Application filed May 21, 1924, Serial No. 714,782, and in Great Britain May 30, 1923.

The present invention relates to improvements in addressing or like printing machines of the type wherein stencil cards are employed for printing names and addresses upon wrappers, labels or the like.

In addressing machines of this class a stencil card is removed from the hopper or magazine through the action of a reciprocating pusher member working in a slide-way or track which pushes the card along the slideway to a position between a segmented inking roller and a segmented presser roller where a label or wrapper is pushed under the card by hand, so that when the inking roller and the presser roller meet they press the wrapper or label between them and print thereon from the stencil.

Presenting each label or wrapper by hand is tedious and the present invention has for its object to adapt an addressing or printing machine of the type referred to so that prints may be produced on a web of paper issuing from a roll and then cut into lengths suitable as labels or wrappers.

According to the present invention a roll of gummed or plain paper is placed in the machine, and the end of the paper is passed between rollers which draw the paper from the roll by mechanism actuated on the forward movement or throw of the crank of the reciprocating pusher member; the paper receives the address or other matter and is then automatically cut off into predetermined lengths by a guillotine which is actuated by mechanism at the finish of the forward throw of the pusher member crank shaft.

The invention will now be described with reference to the accompanying drawings which for convenience show the invention as applied to a Roneo addressing machine.

Fig. 1 is a perspective view of the machine.

Fig. 2 is a plan viewed from underneath the machine.

Fig. 3 is a front view of part of the machine showing the guillotine blade operating to cut the printed wrapper or label from the web.

Fig. 4 is a similar view but showing the guillotine blade after having completed the cutting operation.

Fig. 5 is a fragmentary plan view showing the position of the rollers for drawing off

a pre-determined length of paper from the roll.

Fig. 6 is a fragmentary plan view of the paper roll mounted on its supports.

Fig. 7 is a detail view of parts of the apparatus.

Fig. 8 is a diagrammatic view of the mechanism for operating the reciprocating pusher member and the paper draw-off rollers.

Figs. 9 and 10 are fragmentary views showing the mechanism for operating the guillotine.

On the drawings A, represents the framework of the addressing machine, B, the hopper or magazine for the stencil cards, C, the inking rollers, and D, the slideway or track. The reciprocating pusher member E, which works in the slideway D, is connected by arms 1 to a crank shaft 2, the connecting rod 3 of which is reciprocated by means of a pitman connection with the gear 4, the said gear being driven by a gear wheel 5 to which is fitted the operating handle 6. The reciprocating pusher member E on its forward stroke pushes a stencil card from the hopper B along the slideway or track D to a position between a segmented inking roller F and a segmented presser roller G (see Fig. 2) the segmented inking roller F receiving ink from one of the inking rollers C.

At the back of the machine a roll of gummed or plain paper 7 is supported in brackets 8. The end of the paper roll is passed beneath the hopper B, between the side rails of the track D, between the segmented rollers F and G, under roller X, and between roller 9 and roller 10 (see particularly Fig. 5), the said rollers being carried in brackets 11 at the front end of the machine, the lower roller 10 being driven by a pinion 12 engaged by a reciprocating rack 13. The extreme end of the paper 7 is passed between the guillotine blades 14 and 15, the blade 14 being affixed to the brackets 11 carrying the rollers 9 and 10 while the other blade 15 is pivoted at 16 at one end in a lug carried by one of the brackets 11, while the free end of the blade projects through a slot H formed in a lug 17 carried by the other bracket, and passes through a skew slot J formed in a lever 18 which is pivoted at K to a convenient part of the framework A, and is acted upon by a cam

presently to be described. The slot J in the lever 18 is necessary as it carries the extremity of the guillotine blade 15. If the slot was made perpendicular the arc traversed by the member 18, when acted upon, would tend to distort the guillotine blade 15 on its downward movement.

The reciprocating rack 13 is housed in a guide 19 and passes through a slot formed in 10 the framework A of the machine, and is slotted as at 20 (Fig. 7) to receive a movable lug or bracket 21 on to which is affixed an adjusting screw which determines the length of throw of the rack 13. At the 15 rear of the rack a stationary bracket 23 is affixed which is contacted by the rocking crank member 2^a as the latter moves rearwardly, force the rack 13 into its backward position. On the forward throw of the 20 pusher member E, the crank 2^a comes into contact with the movable lug 21 affixed in the slot 20 of the rack 13 and affords a forward movement to the rack. The rack moving forward on the pinion 12 causes rotation of the lower feed roller 10 and also 25 the upper feed roller 9 which is in frictional contact with it, and so a strip of paper 7 is fed through between the guillotine blades 14 and 15.

30 At the finish of the forward stroke of the rack 13 the guillotine blade 15 is brought into cutting action by means of a cam 24 (Figs. 9 or 10) mounted or formed on a spindle 25 to which a gear 26 is attached, 35 which gear is engaged by a further gear 27, in mesh with the hand operated gear 5, upon which is mounted the segmented presser roller G.

40 On the upper or moving guillotine blade 15 is attached a spring wire 28, see Fig. 5, which holds the paper 7 down when the cutting is effected. The lower roller 10, which is preferably rubber coated is fitted with a clutch or free wheel of known type which 45 permits the roller to remain stationary during the rearward movement of the rack 13.

The adjustment of the feed of the paper 7 is effected by turning the adjusting screw 22 at the end of the machine so that the 50 movable lug 21 moves backwards or forwards in the slot 20 of rack 13 (see Figs. 2 and 7). It therefore follows that if a counter clockwise movement is given to the screw 22, the rack 13 is afforded a greater movement 55 and paper of a length sufficient to form a wrapper will be printed upon and cut. On the other hand if a clockwise rotation is imparted to the screw 22 a lesser movement of the rack 13 is occasioned by the crank 2^a 60 so that a short strip or label is automatically cut. Y is the adjustable envelope gauge.

In action, a roll of paper 7 having been mounted in the brackets 8, the screw 22 is turned to afford the necessary adjustment for either wrappers or labels. The end of the 65

paper is passed under the hopper or magazine B and between the segmented inking roller F and presser roller G, under roller X and between the feed rollers 9 and 10 carried between the brackets 11, the extreme 70 edge projecting between the guillotine blades 14 and 15.

A clockwise rotation is now imparted to the handle 6 and the gear 4 operates the 75 pusher member E through the connecting rod 3, crank shaft 2 and arms 1. The crank 2^a of crank shaft 2 in its forward movement engages the movable lug 21 and causes a forward movement to the rack 13 which rotates the pinion 12 and causes the lower roller 10 to revolve and draw off the paper from the roll between it and roller 9.

Simultaneously with this movement, the reciprocating pusher member E acts upon the lowermost stencil card in the hopper B 80 and pushes it to printing position between the segmented inking roller F, which has contacted with the large inking roller C, and the segmented presser roller G. The meeting of the segmented rollers causes the stencil card to print on the paper web 7. Simultaneous with the printing on the paper web, the cam 24 mounted on the shaft of gear 26 (see Fig. 10) acts on the pivoted 85 lever 18 and depresses the free end of the lever against the action of spring 18^a so that the guillotine blade 15 severs the previously 90 printed portion from the web as the top of the slot J acts on the free end of the pivoted blade 15.

95 During the cutting of the printed strip from the web 7 the rollers 9 and 10 remain stationary since the rack 13 has reached its furthest forward movement from the crank 2^a, and the rollers moreover remain stationary on the rearward movement of the rack 13 owing to the free wheel device fitted to 100 roller 10 previously mentioned.

105 It is to be understood that although the invention has been described as being applied to a Roneo addressing machine it can be applied to other types of machines wherein stencil cards are pushed to printing position between a segmented inking roller and a segmented presser roller, the application of the invention only requiring minor alterations or modifications.

110 To turn the machine into use for addressing envelopes it is only necessary to withdraw the paper from the rollers 9, 10 and 115 re-wind on to the paper roll at the end of the machine. Envelopes can then be fed by hand between the segmented presser roller G and the segmented inking roller F.

120 Having thus described my invention what I desire to secure by Letters Patent of the 125 United States is:—

1. In an addressing or printing machine of the type specified, the combination of a 130 paper-supporting roll, a reciprocating stencil

pushing member, draw-off rollers for said paper, a pinion carried by one of said rollers, a rack for operating said pinion, and mechanism for reciprocating said pushing member and for actuating said rack.

2. In an addressing or printing machine of the type specified, the combination of a paper-supporting roll, means for withdrawing a predetermined length of paper from 10 said roll, said means including draw-off rollers, a pinion carried by one of said roll-

ers, a rack engaging said pinion and having a slot therein, a lug fitted in said slot and adjustable longitudinally thereof, a screw member supported by said rack for adjusting 15 said lug, and means contacting said lug to move said rack to operate said pinion, the adjustment of said lug determining the amount of movement of the rack.

In testimony whereof I have signed my 20 name to this specification.

SAMUEL GEORGE WILLIAM PHIPPS.
